UNITED STATES PATENT OFFICE

2,347,811

SORTING DEVICE

Roger Connor and Nelson S. Welk, Athens, Ohio,
assignors to The McBee Company, Athens, Ohio,
a corporation of Ohio

Application March 20, 1943, Serial No. 479,850

15 Claims. (Cl. 129—16.1)

This invention relates to a device for the manual sorting of marginally punched cards. More particularly, it relates to a sorting plate to be used in connection with either selectively or sequentially sorting a relatively large group of cards, having one or more rows of perforations along at least one edge, notched or slotted according to a predetermined code. Cards of this type are illustrated by the disclosure appearing in United States Patent No. 2,213,607 issued to D. A. Nevin, September 3, 1940.

Heretofore, sorting a group of cards of this general type has been accomplished through the use of card supports utilizing movable bottoms and removable master plates or templates. This type of sorting device and its operation has been generally illustrated and described in United States Patent No. 2,299,566 issued to Connor and Nevin, October 20, 1942.

An object of the present invention is to provide a sorting device for use with cards of the type above described which will be compact and readily portable for use in the field, as well as in offices.

Another object of the invention resides in the construction of a lightweight, rugged, one-piece sorting plate which will function efficiently without requiring the use of a movable or drop bottom structure in conjunction with one or more master plates.

Another object is to provide a sorting device combining in a unitary structure aligning means whereby a group of cards, for example, having a double row of perforations notched or slotted, as described in the above said Patent No. 2,213,607, can be readily sorted.

These and other objects and advantages, not at this time more particularly enumerated, will be apparent from the following detailed description, in conjunction with the appended claims, and the accompanying drawings forming a part of this specification.

An illustrative embodiment disclosing a sorting device made according to this invention is shown in the accompanying drawings, in which like numerals are employed to designate like parts throughout, and in which only a preferred example of the invention has been illustrated:

Fig. 1 is a perspective view of a card sorting device embodying one form of the present invention;

Fig. 2 is a sectional end view of the right end of the device illustrated in Fig. 1;

Fig. 3 is a front elevation showing a group of cards having the sorting device illustrated in

Fig. 1 mounted thereon, and illustrating the method of aligning the multiple selectors or needles preparatory to insertion;

Fig. 4 is a perspective view showing a group of cards with the sorting device of Fig. 1 held in place thereon by the operator, and illustrating the manner in which the multiple needle sorter is inserted;

Fig. 5 is a perspective view showing a modified form of sorting device constructed according to the present invention; and

Fig. 6 is a sectional end view of the right end of the device as viewed in Fig. 5.

Referring now more particularly to the drawings, whenever applicant refers to the term "card" or "cards" it is to be understood that items such as, sheets, checks or slips and the like may be substituted as will be understood by those familiar with the art. These terms are also meant to include said additional meanings when used in defining the scope of the invention in the subjoined claims.

In general, as shown in Fig. 1, the card sorting plate is formed from an angle member whose sides 10 and 11 are integrally joined together to form a right angle. Triangular shaped end pieces 12 and 13 are integrally joined to the sides 10 and 11 at their ends to enclose this structure, and provide stops against which the group of cards can be jogged for aligning purposes. Openings 14 and 15 cut through the sides provide fingering space for the operator and thereby facilitate separating the cards, and insuring that a complete sort will be made.

Bored through side 10 at spaced intervals are a row of holes 16 positioned below and parallel to the apex 17, formed by the joining of the sides 10 and 11, which extend clear across the sorting plate. Where, for example, cards of the type generally illustrated and described as in Patent No. 2,213,607 are used, these holes 16 correspond in number and register with the lower or inner row of perforations when the sorting plate is held in relation to a group of such cards as shown in Fig. 4. Adjacent to the upper right hand corner of side 10, Fig. 1, and above and diagonally to the right of the holes 16, a single hole 18 is provided for the insertion of a sorting needle or rod to remove certain selected cards as will be more fully described hereafter.

A row of holes 19, similar to those at 16, are bored through side 11. These are also regularly spaced, parallel to and positioned below the apex 17, but correspond in number and are in register with the upper or outer row of perforations in

the cards when the sorting plate is reversed so that side 11 is placed parallel to the front of the cards. Adjacent to the left hand corner of side 11, as viewed in Fig. 1, and diagonally positioned away from the row of holes 19 is a corner hole 20, positioned to function in a similar manner to hole 18.

Welded to sides 10 and 11 are angle plates 21 and 22, see Figs. 1 and 2. Each plate is notched, as at 23, along its upper edge to provide a guiding or aligning means for the sorting needles. Notches 23 in angle plate 21 correspond in number to the holes 16 in side 10, while those in angle plate 22 correspond in number to those in side 11. Since the row of holes 16 corresponds and aligns with, for example, the inner or lower row of perforations in a card of the type having a double row of perforations along one or more edges; angle plate 21 is positioned a sufficient distance below the apex 17 so that, when the sorting plate is held as illustrated in Fig. 4, the needles 24 in the multiple holder 25 can be inserted through the notches 23 and the holes 16 parallel to side 11. Similarly angle plate 22 is positioned with respect to the apex 17 so that when the sorting plate is reversed, with side 11 to the front, the sorting needles 24 can be inserted through notches 23 and holes 19 parallel to side 10.

The multiple holder 25 having a plurality of 30 sorting needles 24 removably held therein is of a type based upon the disclosure of a similar type sorting device appearing in United States Patent No. 2,261,719 issued to Connor and Nevin, November 4, 1941, and is used in the same manner as described therein. For this reason further description of holder 24 is not believed to be necessary in this specification.

Fig. 3 illustrates the position in which the holder 25 is held, preparatory to inserting the 40 needles 24 through the group of cards 36 to be sorted. In this way the needles, which are somewhat flexible, can be rested in the notches 23 of both angle plates 21 and 22 and held in proper position as the holder is drawn back. When the tips of the needles clear the upper angle plate they are in proper position to be readily inserted through the row of holes aligned directly behind the notches in the lower angle plate. The sorting of the cards can then be accomplished in the usual manner. Corner holes 18 and 20 enable the operator to insert a single sorting needle to remove certain cards sorted in a manner as described in the above said Patent No. 2,213,607.

A modified form of the present invention is 55 illustrated in Figs. 5 and 6. The card sorting plate is formed with a pair of side members 26 and 27 held in spaced relation with respect to each other by means of truncated triangular shaped end pieces 28 and 29 welded to these side members at each end thereof. Flanged edges 30 are provided on these end pieces to facilitate securing the side members in proper position.

The upper edges of side members 26 and 27 are bent as at 31 and 32, and have a plurality of 65 notches 33 cut along their outer edges. These notches correspond in number and are so positioned that those, for example, in upper edge 32 can be used to align the sorting needles 24 of holder 25 for insertion in the upper row of perforations, while those in upper edge 31 are positioned for sorting through the lower row of perforations in the group of cards to be sorted. Thus when this sorting plate is held in position with respect to a group of cards 36, similar to 75

the position shown in Fig. 4, the sorting needles 24 may be aligned across the edges 31 and 32, drawn back and inserted directly into the group of cards in the same manner as previously explained in connection with Fig. 3. For the same purpose and reason, as above described, with relation to corner holes 18 and 20, similar corner sorting holes 34 and 35 are provided in this modified structure.

10 While a specific embodiment of the present invention has been described, it is to be understood that the form herewith shown and described is a preferred example only and that various modifications may be made therein without materially departing from the spirit of the invention as defined by the appended claims.

Having thus described the invention, we claim:

1. A plate for facilitating the sorting of perforated and slotted cards comprising an elongated member having two sides forming substantially a right angle with respect to each other, said sides connected at their ends by a cross piece, and guide means located on each of the said sides adjacent said angle.

20 2. A plate for facilitating the sorting of perforated and slotted cards comprising an elongated member having two sides forming substantially a right angle with respect to each other, said sides connected at their ends by a cross piece, and notched aligning guides located on each of the said sides at relatively different positions with respect to said angle.

3. A plate for facilitating the sorting of notched and slotted cards containing upper and lower rows of marginal perforations comprising an elongated member having two sides forming substantially a right angle with respect to each other, said sides connected at their ends by a cross piece, and the upper edge portions of said sides having elements formed with a plurality of notches therein positioned in such a way that those on one edge portion can be used as guides for the upper row of perforations and those on the other edge portion can be used as guides for the lower row of perforations.

4. A device of the character described for facilitating the sorting of perforated and slotted cards comprising an elongated triangular prism shaped member having a row of regularly spaced holes 50 extending along one edge thereof, and a notched plate secured to said member parallel to said row of holes.

5. A device of the character described for facilitating the sorting of perforated and slotted cards comprising an elongated triangular prism shaped member having a row of holes positioned therein at spaced intervals along one edge; and a plate 65 notched along one edge fastened so as to extend longitudinally across said member parallel to said row of holes, the notched edge of said plate bent in such a way that it is spaced away from said row of holes.

6. A device of the character described for facilitating the sorting of perforated and slotted cards comprising an elongated member having two sides joining to form substantially a right angle, said sides closed at their ends by pieces integrally joined thereto, a plurality of regularly spaced holes extending along one of the said sides, and a plate attached to the last said side having one edge thereof extending away from said holes containing a plurality of notches corresponding in number and aligning with said holes.

7. A device of the character described for facilitating the sorting of perforated and slotted

cards comprising a pair of elongated members joined to form substantially a right angle; and a plate fastened to each said elongated member and extending longitudinally parallel to the apex formed by joining said elongated members, each plate having an edge portion adjacent said apex and containing a plurality of notches therein.

8. A device of the character described for facilitating the sorting of perforated and slotted cards comprising an elongated member having two sides joining to form substantially a right angle, a row of holes in each of said sides extending parallel to the apex formed by joining said sides, a single hole in each of said sides diagonally adjacent to the end of said row of holes therein, and an elongated plate having notches extending along one edge thereof fastened to each side in such a way that said notches are in alignment with the holes in said row.

9. A plate for facilitating the sorting of perforated and slotted cards comprising an elongated member having two sides joining to form substantially a right angle, each of said sides having an opening therein to provide fingering space, a row of holes in each of said sides extending parallel to the apex formed by joining said sides, and an elongated plate having notches extending along one edge thereof fastened to each side in such a way that said notches are in alignment with the holes in said row.

10. A plate for facilitating the sorting of perforated and slotted cards comprising an elongated member having two sides joining to form substantially a right angle, said sides closed at their ends by pieces integrally joined thereto, a row of holes in each of said sides extending parallel to the apex formed by joining said sides, a single hole in each of said sides diagonally adjacent to the end of said row of holes therein, and an elongated plate having notches extending along one edge thereof fastened to each side in such a way that said notches are in alignment with the holes in said row.

11. A plate for facilitating the sorting of perforated and slotted cards comprising an elongated member having two sides joining to form substantially a right angle, said sides closed at their ends by pieces integrally joined thereto, a row of holes in each of said sides extending parallel to the apex formed by joining said sides, each of said sides having an opening therein to provide fingering space, and an elongated plate having notches extending along one edge thereof fastened to each side in such a way that said notches are in alignment with the holes in said row.

12. A plate for facilitating the sorting of perforated and slotted cards comprising an elongated member having two sides joining to form substantially a right angle, said sides closed at

their ends by pieces integrally joined thereto, a row of holes in each of said sides extending parallel to the apex formed by joining said sides, a single hole in each of said sides diagonally adjacent to the end of said row of holes therein, each of said sides having an opening therein to provide fingering space, and an elongated plate having notches extending along one edge thereof fastened to each side in such a way that said notches are in alignment with the holes in said row.

13. The combination with a holder having a plurality of sorting needles mounted therein to facilitate the sorting of cards containing upper and lower parallel rows of marginal perforations adapted to be notched and slotted according to a predetermined code: of an elongated member having two sides joining to form substantially a right angle, said sides closed at their ends by pieces integrally joined thereto, and the upper edge portions of said sides having elements formed with a plurality of notches therein positioned in such a way that those on one edge portion can be used as guides for the upper row of perforations and those on the other edge portion can be used as guides for the lower row of perforations.

14. The combination with a holder having a plurality of sorting needles mounted therein to facilitate the sorting of cards containing upper and lower parallel rows of marginal perforations adapted to be notched and slotted according to a predetermined code: of an elongated member open at the top having two sides joining to form substantially a right angle with respect to each other, the upper edge portions of said sides having elements formed with a plurality of notches therein positioned in such a way that those on one edge portion can be used as guides for the upper row of perforations and those on the other edge portion can be used as guides for the lower row of perforations, and a single hole in each of said edge portions at one end thereof adjacent to said notches.

15. For use with a sorting needle holder, a plate for facilitating the sorting of perforated and slotted cards comprising an elongated member having two sides, means for joining said sides in angular relationship to receive a group of cards to be sorted, said joining means providing ends to close the receiving space between said sides, and each of said sides being provided along its upper edge with a plurality of notches positioned to receive said sorting needle and so arranged and of such extent that said notches can be used as guides for the respective rows of perforations in the cards.

ROGER CONNOR.
NELSON S. WELK.
